UNITED STATES PATENT OFFICE.

ALBERT H. TINNEMAN, OF CLEVELAND, OHIO.

STOVE-TOP CONSTRUCTION.

Application filed February 4, 1927. Serial No. 165,833.

Gas ranges have heretofore been made with either the open top or solid top grate frame construction. To change an open top to a closed top range, it has been necessary to dismantle substantially the entire stove and to break the connections which hold the enameled panels in place. The solid top stove is frequently more desirable since it permits the escape of the products of combustion to the flue in a more effective manner than the open top range. Experiments have indicated however, that in most ranges, the distance between the burner and the article to be heated is not sufficient to insure the greatest efficiency in the transfer of heat.

An object of the present invention therefore is to provide means for enabling an open top to be readily converted into a closed top range. In this connection, my invention is directed toward the use of a closed or solid top construction by means of which the products of combustion may be effectively conveyed to the flue, and the operating efficiency in so far as the transfer of heat is concerned may be substantially increased.

In the drawings Fig. 1 is a perspective view of a part of a stove having an open top grate; Fig. 2 is a perspective view of a part of a stove showing the manner of connecting the grate frame and short panel to the oven structure; Fig. 3 is a perspective view showing the solid top embodying my invention, in place of the open top grate, while Fig. 4 is a perspective view similar to that shown in Fig. 2 and shows the solid top attachment in place of the open top grate frame, and Fig. 5 is a horizontal section through the connection between the oven frame and filler plate.

The range shown in Fig. 1 has a frame 10 on which an open top grate frame 11 is supported. As shown in Fig. 2 this grate frame has a lug 12 through which a threaded securing member 13 may extend. This securing member functions to lock the oven frame 14 to the grate frame. Surmounting the grate frame is a filler plate 15 and a side panel 16. The filler plate is preferably a cast member having inturned flanges along the top and bottom edges and also along the end edges. The end flanges engage the respective front and rear oven frames, while the top and bottom flanges engage respectively the panel 16 and the grate frame 11.

The panel 16 is preferably an enameled member, while the filler plate 15 is preferably made of an aluminum alloy.

The filler plate is arranged to be removable preferably independently of the panel 16, and without disturbing any of the lining or burner connections. To this end, I provide flexible connecting means between the filler plate and the front and rear frames. One suitable connection is shown in Fig. 5 as comprising a screw threaded member 21 which is carried by each flange 22 and is arranged to engage a recess 23 in the associated end frame member. To remove such filler plate, it is only necessary to loosen the member 13 sufficiently to allow the filler plate to be withdrawn from engagement with the frame. By loosening the member 13 the rear frame being flexible may be sprung outwardly at the mid-portion until it clears the head of the member 21.

When the fillerplate is removed, then the grille work upon the open top frame may also be removed and a solid top member 20, having lugs 24 thereon, may be inserted into the grille receiving recesses upon the grate frame. These lugs are spaced at proper intervals to afford an even bearing for the top 20, and are sufficiently long to bring the plane of the upper surface of the solid top 20 above the plane of the top surface on the grate frame. In this way I increase the effective distance between the burner and the bottom of the article to be heated.

To exhaust the products of combustion, I prefer to extend the end portion 25 upwardly so as to effect a snug engagement with the bottom flange of the panel 16. Thus, the space formerly occupied by the filler plate provides a passageway which affords communication between the bottom of the solid top and the flue 30. Moreover, since that portion of the top adjacent the oven is extended upwardly, then the products of combustion have a natural easy passageway along the under surface of the top to the flue, and objectionable pockets beneath the top are thereby avoided.

By making a stove in accordance with my invention, an open top grate range may be readily converted into solid top range merely by removing a filler plate, together with the grille work on the grate frame, and substituting an attachment in the nature of a solid top, in place of the grille work. This

change can be readily effected in an expeditious manner without disturbing the lining or burner connections, or any of the large panels.

5 I claim:

1. In a stove, the combination with a grate frame, of a removable grille mounted thereon, and a solid top adapted to be interchangeably positioned with the grille upon 10 the frame, said top having the plane of the upper surface thereof disposed above the plane of the upper surface of said frame, and having a gas passageway associated with one edge thereof.

15 2. In a stove, the combination with a grate frame having an open-work grille thereon, a solid top removably positioned upon the frame and having the plane of the top surface thereof disposed above the plane of 20 the top surface of said frame, and having a gas passageway extending along one edge thereof.

25 3. In a stove, the combination with a grate frame, of a removable solid top adapted to be positioned upon the frame in such manner that the plane of the upper surface of the top is disposed above the plane of the upper surface of the frame, said top being extended upwardly adjacent one edge thereof, and providing a gas passage-way extending entirely along one edge of the top.

30 4. In a stove, the combination with a grate frame, of an oven panel surmounting the frame, a removable top adapted to be positioned on the frame and to engage said panel, the plane of the upper surface of the top being disposed above the plane of the upper surface of the frame, and there being a portion of the top engaging the bottom of

40 said panel and cooperating with a part of the frame to provide a gas passage-way, said passage-way extending substantially the entire width of said panel.

45 5. In a stove, the combination with a flue, of a grate frame, an oven side panel surmounting the frame, a removable filler plate disposed between the panel and frame, a stove top adapted to be positioned upon the frame having a portion thereof arranged to enter the filler plate space when the filler 50 plate is removed, said portion cooperating with the panel and frame to provide a gas passage-way between the under side of the top and the flue.

55 6. In a stove, the combination with a grate frame, of a panel surmounting the frame, a filler plate cooperating with the panel to form one wall of an oven structure, said plate being disposed between the panel and frame, flexible means for holding the filler plate in position but permitting removal of same without disturbing the panel connections, a stove top adapted to be positioned upon the frame and having the plane of the upper surface thereof disposed above the 60 plane of the upper surface of the frame and having the edge portion near the oven extending upwardly and into the space occupied by the filler plate, said filler plate being removable when the top is positioned 65 on the frame, said upwardly extending portion of the top cooperating with the panel and frame to provide a gas passage-way, and said passage-way extending substantially 70 across the entire width of said panel.

75 In testimony whereof, I hereunto affix my signature.

ALBERT H. TINNERMAN.
